UNITED STATES PATENT OFFICE.

JOHN A. JOHNSON, OF BROOKLYN, NEW YORK.

COMPRESSING AND PACKING MACHINE.

Application filed January 27, 1928. Serial No. 249,869.

This invention relates to means for imparting reciprocatory movement to a slidable member, such as a plunger carrier, and while the invention is particularly adapted to apparatus for packing granulated or comminuted material, such as cork with a binder into stick form, it is also applicable to other apparatus, and it is the object of the invention to provide means to impart to a slidable member reciprocatory movement in series of successively decreasing extent. The application is a continuation in part of my co-pending application Serial #179,764, filed March 31, 1927.

In carrying out the invention I have illustrated the same as embodied in apparatus for packing comminuted cork into stick form wherein a series of tubes are carried in a support therefor and successively positioned by the support with the opposite ends relative to material carrying pockets to which material is fed from a hopper or hoppers, and from which pockets the material is delivered and packed into opposite ends of the tubes as successive increments by plungers mounted in reciprocatory carriers in line with the material carrying pockets, the tubes carrier or support being adapted to be operated after a series of successive movements have been imparted to the plunger carriers and the tubes filled with comminuted material to advance the filled tubes and position further tubes to be filled relative to the material carrying pockets.

In the drawings accompanying and forming a part of this specification Figure 1 is a side elevation, partly in section and partly broken away, of a comminuted cork packing apparatus embodying my invention.

Figure 2 is an end elevation looking at the right of Figure 1.

Figure 3 is a side elevation, on an enlarged scale and partly broken away of the right hand section of the apparatus shown in Figure 1.

Figure 4 is a plan view looking at the top of Figure 3; and

Figures 5, 6 and 7 are detail views in perspective of parts for operatively connecting the plunger carrier operating means to actuating means therefor.

I have illustrated my invention in connection with apparatus for packing granulated or comminuted cork mixed with a binder into tubes to form sticks from which disks are sliced to constitute the lining of closure

caps for receptacles as described and illustrated in Patent No. 1,477,358 dated December 11, 1923, wherein a series of tubes 8 are supported at the opposite ends by a turret 60 comprising a pair of wheels 9 having recesses disposed about the periphery and mounted in spaced relation upon a rotatable shaft 10, and by means of which support the tubes seated in the peripheral recesses are positioned with the ends in line with pockets 11 arranged in an arc of a circle coinciding with the tube receiving recesses in the turret wheels, said pockets being disposed below hopper outlets 12 to receive material therefrom. The tube support is intermittently rotated from a drive shaft 13 by a pinion (not shown) on said shaft meshing with a gear 14 fixed to a shaft journaled in a bracket 15 fixed to the base of the framework, a wheel 16 also fixed to said shaft having a section of teeth 17 adapted upon each revolution of said wheel to mesh with a pinion 18 fixed to a shaft journaled in an upwardly extending portion 19 of the bracket 15, the shaft carrying the pinion 18 also having a pinion 20 fixed thereon to mesh with a gear 21 fixed on shaft 10, the ratio and timing of the gearing being such so that the tube carrying support will have an intermittent movement imparted thereto, the distance the support is moved being the space occupied by six notches to move filled tubes (6 in number) away from the material receiving pockets and position another series of tubes relative to said pockets 90 upon the imparting of a predetermined series of reciprocatory movements to a series of plungers 22 to deliver material from the pocket 11 into the end of the tubes carried by the support. The shaft 13 is driven from a drive shaft 23 by a pinion 24 on said latter shaft meshing with a gear 25 on shaft 13. The drive shaft 23 is driven from a suitable source of power by a belt passing around a pulley 26 loosely mounted on said shaft and adapted to be connected to said shaft by a clutch mechanism 26' of the ordinary type. The plungers 22 are mounted at one end in a carriage or carrier 27 slidably mounted and guided for reciprocatory movement by two pairs of rollers 28, 29 at the opposite ends of the carrier upon parallel rods 30 fixed in the frames, one roller of each pair engaging above and the other roller below the rods. There are two plunger carriers one arranged 110 at the outer side of each series of pockets 11 and as both of said carriers, the mounting

and operating means therefor, are the same description one will suffice for both.

The comminuted cork is delivered from the pockets 11 into the tubes by the plungers 22 in successive increments to compensate for the increased quantity of material in the tubes, cork delivering and packing means are provided to impart to the plungers movements of successive variable decreasing extent in the delivery movement thereof from a predetermined position of rest and returned to said position.

The means for transmitting movement of successive variable decreasing extent to the plunger carrier 27 comprises a stepped cam member in the form of a disk 31 having peripherally and radially disposed stepped faces 32. This stepped cam member is fixed to a shaft 33 rotatable on an axis transverse to the plane of movement of the plunger carrier, and is rotatably mounted in a boss 34 of a slide 35 mounted to have reciprocatory movement in the plane of movement of the plunger carrier in a slideway 36 of a bracket 37 and reciprocated through the rotative movement of a shaft 38 rotatable on a vertical axis and driven from a shaft 39 by bevel gearing 40, said shaft 38 carrying a disk 41 and operatively connected with the slide 35 by a link pivotally connected at 42 with the slide and at 43 with the disk eccentric to the axis of the disk carrying shaft. The shaft 39 being rotatably connected to the shaft 13 by a chain drive 43'. To impart movements of successive variable extent to the plunger carrier in one direction from a predetermined position of rest and return the carrier to said position there is provided a slidable member 44 having a pivotal connection with the plunger carrier 27 by an arm 45 fixed at one end to the carrier and pivoted at the opposite end to the member 44, and having a lost motion connection with the slide 35 by extending the shaft 33 of the stepped face cam member through a slot 46 in said member 44. As the slide 35 is moved in one direction the shaft 33 will engage with the wall at one end of the slot, as shown in Figure 3, and thereby transmit movement of the slide 35 to the member 44 and plunger carrier. As the slide 35 is moved in the opposite direction there is a slide movement of the slide 35 relative to the member 44 until a stepped face of the cam member engages an abutment 47 fixed to and projecting laterally from the member 44.

To intermittently advance or rotate the cam member one stepped face distance upon each reciprocation of said member, there is provided a wheel 48' slidably arranged with circumferentially spaced tooth sections 48 with intervening curved faces 49 and having a hub portion whereby it is rotatably mounted in a bearing 50 of an arm of the slide carrying bracket 37 with said wheel abutting against one end of the bearing and held

against longitudinal displacement by a collar 51 fixed to the end of the wheel hub projecting from the opposite side of said bearing, said wheel constituting one member of Geneva gearing. The other member of the Geneva gearing is in the form of a wheel or disk 52 arranged with a tooth section 53 to mesh with the tooth sections 48 of wheel 48' to impart an intermittent movement to said wheel 48' upon each revolution of the wheel 52, the curved portions 49 being of a curvature to coincide with the periphery of the disk 52 and the latter serving to hold the wheel 48' against rotation. The wheel disk 52 is fixed to the shaft 39 imparting rotative movement thereto. To transmit the movement of the wheel 48' to the stepped face cam member the shaft 33 carrying said member has a bevel gear 54 fixed thereon meshing with a bevel gear 55 on a shaft 56 rotatably mounted in a bearing of an arm 57 extending downward from the slide 35 and held against longitudinal movement in said bearing by the hub of gear 55 abutting against one side of said bearing and a collar 58 fixed to said shaft at the opposite side of said bearing. By this arrangement the shaft 56 will participate in the reciprocatory movement of the slide 35. The shaft 56 extends through the hub of the Geneva wheel 48' and to permit of axial movement of the shaft and participating movement thereof in the rotative movement of the Geneva wheel the shaft has a key 59 for the slidable engagement of a key carried by the Geneva wheel. The boss 34 and arm 57 of slide 35 are extended through a slot 60 in the slideway 36 to permit of reciprocatory movement of the slide 35. The stepped face cam member is constructed to impart ten material delivery and packing movements to the plunger carrier of successive variable predetermined extent for which purpose the cam member is arranged with ten stepped faces. After the tenth material delivery movement of the plunger carrier the tube carrier wheels 9 are advanced to present a successive series of tubes 8 to the pockets 11 receiving material from the hopper outlet 12, which movement is imparted during the interval of an advancing and retracting movement of the plunger carrier, and while the stepped face member is positioned as shown in Figures 3 and 4 by the rotation of shafts 33, 56, 39 in synchronism with the rotation of shaft 10 in conjunction with shaft 13 and is brought back to its position of rest by the rotation of shaft 38 and disk 41.

It will be obvious that various modifications may be made in construction and arrangement of parts, and that portions of the invention may be used without others and come within the scope of the invention.

Having thus described my invention I claim:

1. The combination with a slidably mounted plunger carrier, of means to impart reciprocatory movements thereto in series of successively decreasing extent embodying a rotatable and reciprocatory cam member arranged with circumferentially and radially disposed stepped faces for successive engagement with the carrier in the reciprocatory movement of the cam in one direction, means to reciprocate with the cam for engagement with the carrier to impart return movement thereto in the reciprocatory movement of the cam in the opposite direction, and means to reciprocate the cam and impart intermittent rotative movement thereto upon each reciprocatory movement thereof.

2. The combination of a slidable plunger carrier, a reciprocatory slide, a peripherally and radially stepped member rotatably mounted on the slide, a slidable member connected to the carrier arranged with a lateral projecting abutment and having a lost motion connection with the slide, and driving means to impart reciprocatory movement of the same extent to the slide and intermittent rotative movement to the stepped member to successively position the stepped faces for engagement with the slidable member abutment and impart successive movement to said member and connected plunger carrier of variable extent in one direction.

3. The combination of a slidable plunger carrier, a member arranged with peripherally and radially stepped faces, a reciprocatory slide on which said member is rotatably mounted, a slidable member having a pivotal connection with the carrier and a lost motion connection with the slide and adapted to move the plunger carrier to a predetermined position in one direction, and the stepped faces adapted to impart movement to said carrier through the slidable member of successive variable extent in the opposite direction, means to reciprocate the stepped face member carrying slide, and means to rotate said stepped face member one stepped face distance upon each reciprocation thereof.

4. The combination with a slidably mounted plunger carrier, of means to impart reciprocatory movements thereto in series of successively decreasing extent, comprising a slide reciprocatory in the direction of movement of the plunger carrier, a cam arranged with peripherally and radially stepped faces carried by the slide to participate in the reciprocatory movement thereof and have rotative movement on an axis transverse to said reciprocatory movement, a slidable member having connection with the carrier and a lost motion connection with the slide and arranged with an abutment for the engagement of the stepped faces of the cam to transmit movement of the slide to the carrier of variable extent in one direction, and means to reciprocate the slide and impart rotative

movement of stepped face distances to the cam upon each reciprocation of the slide.

5. Means to impart reciprocatory movements to a plunger carrier as claimed in claim 4, wherein the means to impart the reciprocatory movement to the cam carrying slide comprises a rotary shaft having a crank connection with the slide.

6. Means to impart reciprocatory movements to a plunger carrier as claimed in claim 4, wherein the means to impart the reciprocatory movement to the cam carrying slide comprises a rotary shaft, a disk fixed to said shaft, and a link having a pivotal connection with the slide and the disk eccentric to the axis thereof.

7. In means to impart reciprocatory movements to a plunger carrier as claimed in claim 4, Geneva gearing operative to impart intermittent rotative movement to the cam upon each reciprocation of the carrying slide, comprising a shaft rotatably carried by and participating in the reciprocatory movement of the slide on which one member of the Geneva gear is mounted to rotate therewith without participating in the reciprocatory movement thereof, a shaft rotatably carried by the slide upon which the cam is fixed and driven from the first shaft, and a driving shaft upon which the other member of the Geneva gear is fixed.

8. Means to impart reciprocatory movements to a plunger carrier as claimed in claim 3, wherein the pivotal connection between the slidable member and the carrier comprises an arm pivotally connected to the slidable member and fixed to the carrier.

9. Means to impart reciprocatory movements to a plunger carrier as claimed in claim 4, wherein the means to reciprocate the slide and impart rotative movement of stepped faces distances to the cam comprises a drive shaft connected to the cam by Geneva gearing and having a crank connection with the slide.

10. In apparatus for packing comminuted cork into stick form, the combination with spaced and aligned material carrying pockets, an intermittently rotatable support for a tube adapted to position the opposite ends of a tube in alignment with the pockets, a pair of slidably mounted plunger carriers operative to actuate plungers carried thereby to deliver the material from the pockets to opposite ends of a tube supported in alignment therewith, and means to impart a series of material feeding movements of successive variable extent to the plunger carriers, comprising a pair of members arranged with peripherally and radially stepped faces mounted to have rotative and reciprocatory movement in the plane of movement of the plunger carrier, means to reciprocate and impart intermittent rotative movement of stepped face distances to said members upon each reciprocatory movement thereof, and

means to actuate the tube support to position another tube relative to the material carrying pockets after each successive series of movements of variable extent have been imparted to the plunger carrier.

11. Apparatus for packing comminuted cork into stick form as claimed in claim 10, wherein the members with the stepped faces comprise disks rotatably mounted on a reciprocating slide adapted to be moved in synchronism with the movement of the tube support.

12. Means for imparting reciprocating movement to a plunger carrier as claimed in claim 1, wherein the cam member is in the form of a horizontal extending disk eccentrically mounted.

13. Means for imparting reciprocating

movement to a plunger carrier as claimed in claim 3, wherein the peripherally and radially stepped face cam member is in the form of a disk extending parallelly to the slide.

14. The combination of a slidable plunger carrier, a member arranged with peripherally and radially stepped faces, a reciprocating slide on which said member is rotatably mounted, a slideway arranged to permit reciprocation of the slide and the mounting for the stepped face member, and means to transmit the reciprocating movement of the slide through the stepped faces to the plunger carrier.

Signed at the borough of Manhattan, in the county, city and State of New York, this 20th day of January A. D. 1928.

JOHN A. JOHNSON.
